UNITED STATES PATENT OFFICE

165,372

GAME INDICATOR

Maxwell Frank, New York, N. Y.

Application April 25, 1950, Serial No. 9,469

Term of patent 3½ years

(Cl. D1—2)

To all whom it may concern:

Be it known that I, Maxwell Frank, a citizen of the United States of America, and a resident of the city of New York, in the county of Queens and State of New York, have invented a new, original, and ornamental Design for a Game Indicator, of which the following is a specification, reference being had to the accompanying drawing, forming a part thereof.

Fig. 1 is a top view of a game indicator, showing my new design; and

Fig. 2 is a front view thereof.

The rear of the design is plain.

I claim:

The ornamental design for a game indicator, substantially as shown and described.

MAXWELL FRANK.
